UNITED STATES PATENT OFFICE.

JAMES BALLARD, OF ALMONT, MICHIGAN.

IMPROVEMENT IN WASHING-MACHINES.

Specification forming part of Letters Patent No. 137,046, dated March 25, 1873.

To all whom it may concern:

Be it known that I, JAMES BALLARD, of Almont, in the county of Lapeer and State of Michigan, have invented a new and useful Improvement in Washing-Machines; and I do declare that the following is a true and accurate description thereof, reference being had to the accompanying drawing and to the letters of reference marked thereon and being a part of this specification, in which—

My invention is shown in perspective from the top, with a portion of the side broken out.

The nature of this invention relates to an improved construction of washing-machines, wherein is used a reciprocating wash-board; and it consists in the peculiar construction and arrangement of a wash-board, secured to the lower ends of reciprocating standards, the upper ends of which are provided with guide-rods, which play through a rock-shaft suitably journaled in standards rising from the wash-box, and in the levers for operating the machine, as is more fully hereinafter set forth.

In the drawing, A represents the wash-box of my machine, mounted on suitable legs B. C is a series of rollers, journaled at their ends in the side pieces a; connecting these pieces a together are wooden rods b, which serve the purpose of keeping the pieces a at a proper distance apart, so that the rollers C may freely rotate in their bearings. These rollers C and the pieces a are placed in the bottom of the box A, being held in position by the rigid stops D and the

eccentric buttons E. F is a rock-shaft, journaled in the upper ends of the standards G, which rise from the sides of the box. H are two reciprocating standards, the upper ends of which are provided with guide-rods I, which pass through holes e in the rock-shaft; to the lower ends of the standards is secured a wash or rub board, J, which is corrugated on its under face. In the standards are slots f, through which are pivoted the hand-levers K; to the short arm of these levers are pivoted one end of the hanging fulcrums L, their other ends being pivoted to the journals of the rock-shaft, as at g.

It will be seen that by constructing a washing-machine in this manner there will be no difficulty in adjusting it to wash fabrics that may be of varying thicknesses, as by raising or depressing the hand-levers K the rub-board will be also raised or depressed, by reason of the reciprocating motion of the guides of the standards through the rock-shaft. The rollers C are arranged on the arc of a circle, of which the rock-shaft is the center.

What I claim as my invention, and desire to secure by Letters Patent, is—

The combination of the lever K with the rub-board J, reciprocating standards H with guide-rods I, hanging fulcrums L, and rock-shaft F, as described.

JAMES BALLARD.
